US0D1041356S

(12) **United States Design Patent** (10) **Patent No.:** **US D1,041,356 S**
(45) **Date of Patent:** **** Sep. 10, 2024**

(54) **FRAME FOR CYCLES OR MOTORCYCLES**

(71) Applicant: **Zhejiang Arctic Leopard Electric Technology Co., Ltd.**, Taizhou (CN)

(72) Inventor: **Gangjun Cai**, Taizhou (CN)

(73) Assignee: **Zhejiang Arctic Leopard Electric Technology Co., Ltd.**

(**) Term: **15 Years**

(21) Appl. No.: **29/882,581**

(22) Filed: **Jan. 17, 2023**

(51) LOC (14) Cl. **12-11**

(52) U.S. Cl.

USPC **D12/110**

(58) **Field of Classification Search**
